United States Patent Office

Des. 221,088
Patented July 6, 1971

221,088

FILING CABINET

Charles M. Huck, New Brunswick, N.J., assignor to
Estey Corporation, Red Bank, N.J.

Original design application Sept. 25, 1968, Ser. No.
13,713, now Patent No. 215,307. Divided and this ap-
plication Sept. 18, 1969, Ser. No. 19,204

Term of patent 14 years

Int. Cl. D6—01

U.S. Cl. D33—19

FIG. 1.

FIG. 2.

FIG. 3.

FIG. 1 is a perspective view of the filing cabinet.
FIG. 2 is a front elevation of the cabinet, while FIG.
3 is a side view of the cabinet.

This application is a division of applicant's earlier filed
application D. 13,713, filed Sept. 25, 1968, and now Patent
No. D. 215,307, and applicant claims the benefit of the
earlier date.

I claim:

The ornamental design for filing cabinet, as shown.
